UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

POWDER-BOX.

1,246,924.

Specification of Letters Patent.

Patented Nov. 20, 1917.

Application filed July 31, 1915. Serial No. 42,896.

To all whom it may concern:

Be it known that I, JOHN M. HOTHERSALL, a citizen of the United States, residing in Brooklyn, in the county of Kings and State 5 of New York, have invented a new and useful Improvement in Powder-Boxes, of which the following is a specification.

This invention relates to powder boxes and has more particular reference to boxes 10 constructed for packaging talcum, face and other finely pulverized powders.

The principal object of this invention is the construction of a lock seam box of the character described which when provided 15 with a tight slip cover will close the box at the cover and body joint in such fashion as to effectually prevent seepage out of any powder down between the abutting folds of the seam and between the body and the 20 cover.

In the construction of a lock seam two folded edges are brought in abutment, by reason of which fact it has been found prior to my invention to be impossible or at least 25 impracticable to eliminate entirely any recess at the seam, and if any recess be present the finely ground talcum or face powder seeps out in transit between the cover and body down through the recess in the seam. 30

An object of this invention therefore is the elimination of or at least material reduction of any seepage of the powder down such recess.

Other objects and advantages of the invention will be apparent as it is better understood from the following description when considered in connection with the accompanying drawing illustrating a preferred embodiment thereof.

On the drawing,

Figure 1 is a side elevation of a powder box embodying my invention;

Fig. 2 is a partial view of the same showing the cover lifted;

Fig. 3 is a section through the top of the body;

Fig. 4 is a section on the line 4-4 of

Fig. 2;

Fig. 5 is a section on the line 5-5 of

Fig. 2;

Fig. 6 is a partial view showing the formation of two edges of the body blank before they are bent;

Fig. 7 is an end view of one edge; and

Fig. 8 is an end view of the other.

In order to illustrate my present invention I have shown on the drawing a talcum powder box of the well known continuously curved form, that is to say, of either circular or elliptical cross section, although of course it may have other desired form. In the present instance the body is formed of a single blank bent to bring its longitudinal edges into adjacent relation where they are interlocked to form a lock side seam. Referring first more particularly to Fig. 6 it will be noted that in the box embodying my invention a tongue 11 is defined by two incisions 12 near one end of one edge 13. The material above and beneath the tongue is bent back on the line 14 to form the hooked edge 15 in Fig. 8, the tongue 11 being permitted to extend out in its original position. The other edge 16 of the blank is bent along the line 17 to form a hook 18 extending in the opposite direction from the hook 15 and adapted for engagement therewith. It is also folded upon the lines 19 and 21 to bring the hook portion into alinement with the outer face of the blank. When thus arranged the hook 15 is inserted within the hook 18 and the parts compressed, as shown in Fig. 5, the tongue 11 extending beyond the seam and over back of the other edge 16. In the compression of the seam, as shown in Fig. 5, the outer portion of the tongue is disposed substantially in the outer face of the surrounding material. A depression 22 is formed in the seam back of the tongue to close the open space provided in the hook 15 through the provision of the tongue 11. This arrangement eliminates or interrupts the recess 23 seen best in Fig. 5 at a point between the cover and body. The tongue 11 as may be seen from Fig. 2 is ordinarily provided just above the outwardly extending pressed bead 24 provided to limit the closing movement of the cover.

It is thought that the invention and many of its attendant advantages will be understood from the foregoing description, and it will be apparent that various changes may be made in the form, construction and arrangement of the parts without departing from the spirit and scope of the invention, or sacrificing any of its material advantages, the form hereinbefore described being merely a preferred embodiment thereof.

I claim:—

1. A powder box comprising a container and a slip cover therefor, said container being provided with a lock seam having a laterally extended lap intermediate its ends, said lap being formed on one edge of the can body and being inset into a recess in the other edge of the can body, so that at the said lap the two seam elements are flush with each other.
2. A powder box comprising a body having a bead near its open end to limit closing movement of a slip cover, said body being formed of a sheet having its edges secured together in a lock seam, said lock seam being interrupted to provide overlapping parts to prevent seeping out of the powder at and near the bead.
3. A powder box comprising a body having a side lock seam and formed of continuously curving walls provided with a bead near the open end of the box, one of the edges interlocked in said seam having a part extending out of the seam and over

across the seam to beyond the edge interlocked therewith.

4. A powder box comprising a continuously curved body having a locked side seam and provided with a bead for limiting movement of a cover, and means comprising a lap formed on one seam element for preventing powder seeping down the outside of said seam and out of the box.

5. A powder box comprising a body having a locked side seam and provided with a slip cover, the lock portion of said side seam being interrupted and formed with a lap and being engaged by the slip cover, to prevent the powder seeping along the seam and between the cover and body and out of the box.

Signed in the presence of two subscribing witnesses.

JOHN M. HOTHERSALL.
